Primary Examiner — Calvin E Vansant*Assistant Examiner* — Benjamin L. Gray(74) *Attorney, Agent, or Firm* — Michael David Eisenberg**CLAIM**

The ornamental design for a saw guide as shown and described.

DESCRIPTION

FIG. 1 is a front, right and bottom perspective view of a saw guide, showing my new design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and bottom perspective view of the saw guide of FIG. 1 shown in an environment of use; and,

FIG. 10 is another rear, left and top perspective view of the saw guide of FIG. 9.

The dashed broken lines depict portions of the saw guide that form no part of the claimed design. The additional broken lines in FIGS. 9-10 depict environmental structures and form no part of the claimed design.

1 Claim, 10 Drawing Sheets(56)
